DESIGN.

—o—
F. MANKEY.

MOLDING.

No. 16,525.

Patented Feb. 16, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,525, dated February 16, 1886.

Application filed November 2, 1885. Serial No. 181,713. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Extending longitudinally upon the surface 10 of the molding is a raised band, A. The edges of said configuration have a similar outline, the same showing a series of scallops. The scallops on one edge are placed opposite the points of meeting of the scallops of the opposite edge. 15 On the surface of the band A are channels or scores B C, which extend diagonally in alternately opposite directions between the meeting-points of the scallops.

The general appearance of the design is that of a series of circular segments placed in juxtaposition, each alternate segment being reversed. 20

I claim—

The design for a molding, substantially as herein shown and described, which consists of 25 the band A, having scalloped edges, and upon its surface channels or scores B C, the same having the appearance of a series of circular segments placed in juxtaposition, each alternate segment being reversed, as shown and 30 described.

FREDERICK MANKEY.
